UNITED STATES PATENT OFFICE.

NORMAN W. CHAFFIN, OF BURNWELL, WEST VIRGINIA.

RAILWAY-SWITCH.

1,383,188.

Specification of Letters Patent. Patented June 28, 1921.

Application filed September 22, 1920. Serial No. 412,040.

To all whom it may concern:

Be it known that I, NORMAN WILBURN CHAFFIN, a citizen of the United States, residing at Burnwell, in the county of Kanawha and State of West Virginia, have invented certain new and useful Improvements in Railway-Switches; and I do hereby declare the following to be a full, clear, and exact description of the invention, such as will enable others skilled in the art to which it appertains to make and use the same.

An object of the invention is to provide a relatively simple and effective switch mechanism, suitable for general railway, urban and interurban use, whereby a switch, normally held closed may be opened readily by means under the direct control of the engineer or motorman or other train or car attendant, and may be held locked in the open position until the train or car, regardless of the length thereof, has entered the switch, whereupon the rails will be returned to the normal or closed position so as not to interfere with subsequent through-traffic without requiring any readjustment, and therefore without the services of a local switchman or watchman, and with these objects in view the invention consists in the construction and combination of parts of which a preferred embodiment is shown in the drawings, wherein:

Figure 1 is a plan view of a section of track embodying a switch mechanism constructed in accordance with the invention.

Fig. 2 is a longitudinal sectional view of the same on the plane indicated by the line 2—2 of Fig. 1.

Figs. 3 and 4 are transverse sectional views on the planes indicated respectively by the lines 3—3 and 4—4 of Fig. 1.

Fig. 5 is a detail view of the locking means.

Fig. 6 is a detail section of the means for normally retaining the locking rail in the switch releasing position.

Figs. 7 and 8 are detail views of a device which may be attached to the train for operating the switch therefrom.

In the illustrated embodiment of the invention, the main or through track-rails are indicated at 10 and the switch rails at 11, the latter being connected by a transverse switch bar 12 connected at one end to a locking member 13 which is terminally disposed

to traverse the rack plate 14, which may as 55 illustrated be supported upon one of the ties 15, said locking member normally being held out of contact with the rack plates but adapted for depression to bring the toothed portion 16 thereof into engagement with the 60 rack plate so as to maintain the switch rails in an open position.

Located longitudinally between the rails of the main track in the direction of approach to the switch rails is a tread rail 17 65 fulcrumed at one end by means of a retaining plate 18 in a plane below that of the treads of the main rails, said tread rail being inclined upwardly as it approaches the switch and projecting to a plane above that 70 of the treads of the track rails, where it is provided with a downwardly extending guide pin 19, operating in a guide socket 20 and actuated by a spring 21 to normally and 75 yieldingly hold the tread rail in the elevated position indicated in Fig. 2. Also disposed longitudinally with reference to the track rails and mounted in suitable bearings 22, which may be secured to the ties or other like supports, is a rock shaft 23 having at 80 one end a crank arm 24 which is connected by a link 25 with the upper or movable end of the tread rail so that when the tread rail is depressed the rock shaft will be turned and through a crank arm 26 at the other end 85 thereof will communicate longitudinal movement to the switch bar 12 to shift the switch rail to the open position.

In connection with the above described mechanism, there is employed a retaining rail 27, of a length greater than the interval between the trucks of any car or train which may traverse the track, said retaining rail preferably being let into the main track rail which as indicated at 28 may be halved or 90 split longitudinally for that purpose, the end 29 of said retaining rail being secured in place so as to permit of a slight vertical vibratory movement and being supported at the opposite end as indicated at 30, by a 95 guide pin 31 operating in a guide tube or socket 32, in opposition to a spring 33 which tends to raise the free end of the retaining rail while permitting the latter to be depressed by the weight of the wheels of a car 100 or train traversing the track. The retaining rail follows the main track rail to the free end of the switch rail arranged in op-

- erative relation therewith, and then follows the switch rail at a sufficient interval therefrom to permit of the opening movement of the said rail, so that when the switch is open a car or train passing from the main track to the switch by reason of the continuous engagement of the wheels thereof with the retaining rail, holds the latter depressed until the wheels of the last car or last truck 10 of the car have passed into the switch.
- Arranged at its free end in the path of downward movement of the retaining rail is a treadle arm 35 suitably fulcrumed or mounted as at 36 upon a convenient cross tie 15 of the roadbed and extending over a swinging bearing arm 37 mounted for example at 38 also upon one of the cross ties and terminally bearing upon the locking member 13 of the switch bar, so that when a train or 20 car approaching the switch depresses the retaining rail, it causes a downward movement of the treadle arm 35 and therefore of the holding arm 37 to correspondingly actuate the locking member 13 to bring it into 25 engaging relation with the ratchet plate 14, so that when the tread bar 17 is depressed and the switch bar, through the connecting mechanism above described, is moved transversely of the line of track to move the 30 switch rails to the open position, said rails are locked in the open position by the engagement of the said locking member 13 with the ratchet plate.

Carried by the car or engine of the train, 35 as for example upon a suitable transverse spindle 39 is a tread roller 40, movable axially with relation to the spindle and connected with a hand lever 41 adapted to be arranged within convenient reach of the engineer or motorman, so that as the car or train approaches the switch, if it is desired to enter the same, the engineer or motorman 40 may operate the lever 41 and thus shift the tread roller 40 into the plane of the tread bar or rail 17 to cause the depression thereof and hence the shifting of the switch rails whereupon the engagement of the wheels of the train or car or engine with the retaining rail will lock the switch rails in this position 45 until the complete train has entered the switch. In the construction illustrated a rod 42 extending from the operating lever 41 is connected with a lever 43 which in turn is connected with a bell crank lever 44 from 50 the extremity of which extends a shifting rod 45 to the tread roll.

It will be obvious from the description that the opening of the switch may be effected without interrupting the movement of the 60 car or train, and after the last wheels of the car or train have released the tread wheel, the switch will be automatically closed by the elevation of the free end of the tread rail and the free end of the retaining rail, so 65 that a through train or car may follow the

main track without any intermediate adjustment or manipulation on the part of an attendant.

Having thus described the invention, what I claim is:

1. A railway switch mechanism having switch rails and means for yieldingly holding the same in their closed position, a rock shaft operatively connected with the switch rails, a vertically movable tread rail disposed in parallelism with the track rails in an upwardly and forwardly inclined position and operatively connected with said rock shaft, said tread rail being yieldingly held in its normal position and being depressible by a car or train carried actuator, a locking means for holding the switch rails in their opened position, and a retaining rail disposed in parallelism with said adjacent portions of the main track and switch rails and depressible by the weight of wheels traversing said rails, said retaining rail being operatively connected with said locking devices. 70 75 80 85 90

2. A railway switch mechanism having switch rails yieldingly held in their closed positions, a vertically movable tread rail operatively connected with the switch rails and actuatable by car or train carried means, a vertically movable terminally depressible and yieldingly supported retaining rail disposed in parallelism with adjacent portions of the main track and switch rails for depression by wheels traversing said rails, locking means consisting of a ratchet plate and a yielding locking member connected with the switch rails and adapted for engagement with the ratchet plate, and a treadle arm operatively connected with the retaining rail and adapted for moving the locking member into engaging relation with the ratchet plate. 95 100 105 110

3. A railway switch mechanism having switch rails yieldingly held in their closed position, a switch bar connecting said rails, locking means for securing the switch rails in their opened position and consisting of a yielding locking arm and a ratchet plate traversed thereby, a tread rail disposed parallel with the track rails for actuation by train or car carried means and operatively connected with said switch bar for moving the latter to the open switch position, a vertically depressible retaining rail disposed in parallelism with adjacent portions of the main track and switch rails for actuation by wheels traversing said rails, an oscillatory operating arm disposed in engaging relation with said locking arm, and a treadle arm operatively connected with the retaining rail and disposed to actuate said operating arm. 115 120 125 130

4. A railway switch mechanism having switch rails and means for yieldingly holding the same in their closed position and returning the same thereto when displaced, a

tread rail operatively connected with the switch rails for actuation by train or car carried means, a stationary locking member, a movable locking member connected to the 5 switch rails, a vertically movable retaining rail adapted to be depressed by the wheels of a train or car, a swinging arm bearing upon the movable locking member, and a treadle

arm bearing upon the swinging arm and engaged by said retaining rail.

In testimony whereof I affix my signature in presence of two witnesses.

NORMAN W. CHAFFIN.
